DOOR CONTROL SYSTEM

Harvey K. Jones, Parkville, Md., assignor to Western Electric Company, Incorporated, New York, N. Y., a corporation of New York

Application September 28, 1949, Serial No. 118,410

4 Claims. (Cl. 268—19)

1

This invention relates to door control systems, and more particularly to systems for interlockably controlling doors of auto courts.

Shipping operations to and from buildings, such as, for example, factories and warehouses, often require having doors to the buildings open for considerable periods of time in cold weather. Two doors have been used so that one or the other of the doors might be closed while the other is open. However, both doors often would be open at the same time. There have been some systems for interlocking the doors so that only one door might be open at a given time but these systems provided no flexibility as to the extent each door could be opened.

An object of the invention is to provide new and improved door control systems.

A further object of the invention is to provide new and improved systems for interlockably controlling doors of auto courts.

An apparatus illustrating certain features of the invention may include a chamber having an entrance doorway and an exit doorway, an entrance door mounted in the entrance doorway for movement between an open position and a closed position, a door mounted in the exit doorway for movement between an open position and a closed position therein, a reversible electric motor for moving the entrance door, a source of electrical power, a limit switch operable by the exit door for preventing operation of the motor when the exit door is not closed, a second reversible electric motor for moving the exit door, a second limit switch operable by the entrance door for preventing operation of the second-mentioned motor when the entrance door is not closed, means for actuating the first-mentioned motor to open and close the entrance door, and means for actuating the second-mentioned motor to open and close the second-mentioned door.

A complete understanding of the invention may be obtained from the following detailed description of an apparatus forming a specific embodiment thereof, when read in conjunction with the appended drawings, in which:

Fig. 1 is a fragmentary, vertical section of an apparatus forming one embodiment of the invention;

Fig. 2 is an enlarged, fragmentary, vertical section of a portion of the apparatus shown in Fig. 1;

Fig. 3 is an enlarged, fragmentary, vertical section taken along line 3—3 of Fig. 1;

Fig. 4 is an enlarged, fragmentary, vertical section taken along line 4—4 of Fig. 1;

2

Fig. 5 is a diagrammatic view of a portion of a control system forming part of the apparatus, and

Fig. 6 is a diagrammatic view of the remainder of the control circuit.

Referring now in detail to the drawings, there is shown therein an interlocking system for controlling the operations of an exterior door 7 and interior door 8 of an auto court 9 (Fig. 1) so that the exterior door cannot be opened if the interior door is open. The system includes a manually operable, momentary switch 10 (Fig. 5) positioned between a grounded conductor and a conductor of a three-phase power line 11 for energizing a holding relay winding 12, and a normally closed limit switch 14 (Fig. 6) closed when the interior door is moved from its closed position and opened by a lug 15 movable by a distributor screw 13 (Fig. 3) driven in synchronization with the interior door when the interior door is closed. If the interior door is open, the limit switch 14 (Fig. 6) is closed and a winding 16 of a relay 17 is energized to close contacts 18. The relay winding 12 is energized when the contacts 18 and the switch 10 are closed, and closes holding contacts 20 to light a lamp 22 indicating to an attendant inside the building that someone is at the exterior door and wishes the attendant to close the interior door. A bell 24 (Fig. 5) is energized only while the switch 10 is held closed.

If the interior door 8 (Fig. 1) is closed so that the switch 14 is open, to open the exterior door 7, one of three sets of manually operable interlocked switch contacts 26 and 27, 28 and 29, and 30 and 31, located outside the exterior door, inside the exterior door and inside the interior door respectively, may be actuated to open one of the contacts 26, 28 and 30 and close the corresponding one of the contacts 27, 29 and 31 to energize a holding relay winding 32 of a relay 33 which closes holding contacts 34 and contacts 36—36 to energize a motor 38 to drive a shaft 37 in a direction to open the exterior door. As the exterior door arrives at its open position a limit switch 40 is opened by a lug 39, movable by a screw 41 driven in synchronization with the movement of the door 7 to stop the motor 38, and a limit switch 42 was closed as the door 7 moved away from its closed position and a lug 43 moved out of engagement with the switch 42 to permit subsequent closing of the door. Closing of the switch 42 causes energization of a relay winding 44 of a relay 45 to close switch contacts 46 in series with an outside thermostatic switch 48 and in parallel with an inside thermo-

static switch 50. The thermostatic switch 50 is closed if the temperature at its location is below room temperature, and the thermostatic switch 48 is closed when the temperature outside the exterior door 7 is below 50° F. When either of these thermostats is closed and a manually operable contactor 47 is in engagement with a contact 49 in series with the thermostatic switches 48 and 50, a relay winding 52 of a relay 53 is energized to close contacts 54-54 to a heater fan motor 56. The motor 56 drives a fan 57 (Fig. 1) of a heater 58 to blow a curtain of warm air across the exterior door opening thereby preventing undue cooling of the motor court. Operation of a heater 55 is controlled by an inside thermostatic switch 59. The contactor 47 also may be set selectively in engagement with a dummy contact 61 and a contact 63 in parallel with the switches 48 and 50 and the contacts 46 of the relay 45. Certain features of the heaters 55 and 58 and the control circuit thereof are disclosed and claimed in copending application Serial No. 118,318, filed September 28, 1949, by H. W. Hubers for "Methods of and Apparatus for Controlling Temperatures of Rooms."

After the exterior door 7 is opened, a truck may be driven up to the interior door 8 and one of manually operable contacts 60, 62 and 64, located outside the exterior door 7, inside the auto court and inside the building, respectively, may be actuated manually to close a corresponding one of contacts 66, 68 and 70 (Fig. 5) interlocked therewith. This energizes a relay winding 72 of a relay 73 to close holding contacts 74 and motor controlling contacts 76-76 to drive the motor 38 in a door-closing direction. When the exterior door gets to closed position, the limit switch 40 is closed and the limit switch 42 is opened to stop the motor 38 and to break the circuit to the relay winding 44. A limit switch 75 (Fig. 4) openable by a lug 77 driven by a screw 78 is closed whenever the door 7 is not fully open to cause energization of an exhaust fan motor 79 (Fig. 6). Deenergization of the winding 44 (Fig. 5) opens contacts 46 to stop energization of the motor 56 by outside thermostat 48.

After the exterior door 7 (Fig. 1) is closed, the interior door 8 may be opened. If it is desired to open the interior door 8 to its fullest extent, one of manually operable contacts 80 and 82 (Figs. 1 and 6) is opened, whereby a corresponding one of contacts 84 and 86 interlocked therewith is closed. This closes a circuit through the closed one of the contacts 84 and 86 through a relay winding 88 of a relay 89 to close relay contacts 90-90 and 92 to cause energization of an interior door motor 94 to drive a shaft 93 in a direction opening the interior door. The interior door is moved upwardly, permitting the limit switch 42 to close, until it has been raised to its wide open position at which time a limit switch 96 is opened by a lug 95 to stop the motor 94. As the interior door was raised to a predetermined partially open position, a limit switch 98 was opened by a lug 97 without affecting the motor circuit. The lugs 95 and 97 are movable by a screw 99 and the screw 13, respectively, in synchronization with the movement of the interior door.

To close the interior door 8, one of manually operable switch contacts 100 and 102 (Figs. 1 and 6) located in the auto court and in the building respectively, is opened, thereby closing the corresponding one of contacts 104 and 106. Closing one of the contacts 104 and 106 closes a cir-

cuit through a relay winding 108 of a relay 109, the limit switch 14 having been closed by opening the interior door. The relay winding 108 then closes motor contacts 110-110 and holding contacts 112 to reverse the motor 94 to close the interior door. As the door is moved closed, the limit switches 96 and 98 are closed successively by movement of the lugs 95 and 97 and the limit switch 14 is opened at the end of the closing movement, thereby deenergizing the motor 94.

To open the inner door to its partially open position only so that time may be saved in the opening of that door in instances when the door 8 need not be fully opened for loading and unloading operations, one of manually operable, momentary switch contacts 120 and 122 is opened, thereby closing the corresponding one of contacts 124 and 126 interlocked with the contacts 120 and 122, respectively, which closes the circuit to a relay winding 128 of a relay 129. This closes holding contacts 130 and contacts 132, and opens contacts 134 to prevent operation of the circuit for opening the door completely. Closing of contacts 130 keeps the relay winding 128 energized, and closing of contacts 132 causes energization of the relay winding 88 to run the motor 94 in a door-opening direction. As the interior door reaches its partially open position, the limit switch 98 (Figs. 3 and 6) is opened by the lug 97 to stop the door at that position.

The interior door may be closed from its partially open position by actuating one of the switch contacts 100 and 102. Closing of the interior door causes the lug 15 to open the limit switch 14, which deenergizes the relay 16 so that contacts 140 reclose to permit the exterior door to be opened. Similarly, when the exterior door 7 is open the limit switch 42 is closed so that the relay winding 44 is energized, thereby opening contacts 142 preventing operation of the interior door 8.

Limit switches 150 (Fig. 6) and 152 (Fig. 5) are openable by manually operative hoists opening and closing the interior door 8 and the exterior door 7, respectively, to stop push button operation of that door being operated by the manually operative hoist therefor. Switch contacts 160 and 162 interlocked with the switch contacts 80 and 82, respectively, protect the windings 88 and 108, which are mechanically interlocked, from strain if both one of the contacts 80 and 82 and one of the contacts 100 and 102 are actuated simultaneously by accident.

Whenever the exterior door 7 is moved away from its fully closed position, the switch contacts 42 are closed to energize the winding 44 to close switch contacts 46 in series with the outside thermostatic switch 48. If the temperature outside the door 7 is below the predetermined minimum temperature at which the switch 48 closes, the switch 48 is closed and causing the relay winding 52 to be energized to close contacts 54-54 to the heater fan motor 56. The motor 56 drives the fan 57 of the heater near the door to blow a curtain of warm air across the door opening thereby preventing undue cooling of the motor court. This occurs whenever the door 7 is open and the outside temperature is below the predetermined value regardless of the inside temperature in the court. If the outside temperature is above said value, above which the court would not be unduly cooled when the exterior door is open, the switch 48 is open and only the indoor thermostatic switch 50 controls the operation of the fan motor 56. Whenever the exterior door

is in its closed position, the relay contacts 46 in series with the switch 48 are open so that the outside temperature then has no effect on the operation of the fan motor 56 (Fig. 5).

Contacts 180 and 182 of a key-operable switch 184 are provided in series with relay windings 44 and 16, respectively. In periods of cold weather the contacts 180 and 182 are closed so that the relays 17 and 45 are operative to interconnect the circuits controlling the opening and closing of the doors. In summer, when no heating of the auto court is needed, the contacts 180 and 182 are opened so that each door may be operated independently of the other and the circuit to the thermostatic switches 48 and 59 is broken. A key switch 190 may be opened in summer to prevent operation of the exhaust fan motor 19 since the exterior door is kept open during warm weather and exhaust fumes from trucks need not be drawn artificially from the auto court.

Operation

Assuming that a truck comes to the outside of the exterior door 7, the driver actuates the contact 26 located outside the exterior door. If the interior door 8 is open, the switch 14 is closed so that the relay winding 16 is deenergized, thereby opening contacts 140 to prevent opening the exterior door and closing contacts 18 so that the bell 22 may be actuated. Assuming the interior door to be open, the exterior door will not open. The driver then closes the switch 10 to light the lamp 22 indicating to an attendant inside that a truck is at the door, and the attendant closes the interior door, which deenergizes the relay winding 16 to close contacts 140 and open contacts 18. Opening of contacts 18 breaks the circuit to the lamp 22. The bell 24 is energized only while the switch 10 is held closed.

The attendant then actuates one of the sets of interlocked contacts 28 and 29, and 30 and 31 located inside the interior door and inside the exterior door, respectively, to open one of the contacts 28 and 30 and close the corresponding one of the contacts 29 and 31 to energize the motor 38 in a direction to open the exterior door. As the exterior door arrives at its open position, the lug 39 (Fig. 3) opens the limit switch 40 to stop the motor 38 and closes the limit switch 42 to permit closing the exterior door.

Closing of the switch 42 (Fig. 5), which is closed whenever the exterior door is not fully closed, causes energization of the relay winding 44 to close switch contacts 46 in series with the outside thermostatic switch 48. The thermostatic switch 59 is closed if the temperature at its location is below the desired room temperature. If the outside temperature is sufficiently below the desired room temperature, the switch 48 is closed. When either of these switches is closed, the relay winding 52 is energized to close the contacts 54-54 to the heater fan motor 56, and the motor 56 drives the fan 57 (Fig. 1) to blow a curtain of warm air across the door opening thereby preventing undue cooling of the auto court.

After the exterior door 7 is opened, the truck backs up to the interior door 8, and an attendant or the driver actuates one of switch contacts 60, 62 and 64 (Fig. 5) to close the corresponding one of switch contacts 66, 68 and 70. This energizes the motor 38 in a door-closing direction. When the exterior door is moved to its closed position, the lug 41 (Fig. 4) causes the limit switch 40 to close, and opens the limit switch 42 to stop the

motor 38 (Fig. 5) and to break the circuit to the relay winding 44. Deenergization of the winding 44 opens the contacts 46 to stop energization by means of outside thermostat 48 of the heater motor 56.

5 The interior door 8 (Fig. 1) then may be opened. If it is desired to open the interior door to its fully open position, one of switch contacts 80 and 82 (Fig. 6) is opened, whereby the corresponding one of switch contacts 84 and 86 is closed. This causes energization of the interior door motor 94 in a direction opening the interior door. The interior door is moved upwardly as viewed in Fig. 1, the lug 15 (Fig. 3) permitting the limit switch 14 to close, until it has been raised to its wide open position at which time the lug 95 opens the limit switch 96 to stop the motor 94. As the interior door was moved past its partially open position, the lug 97 opened the limit switch 98 without affecting the motor circuit.

20 After the truck is loaded or unloaded, one of the switch contacts 100 and 102 (Fig. 6) is opened manually, thereby closing the corresponding one of the switch contacts 104 and 106. Closing the one of the contacts 104 and 106 closes a circuit through the relay winding 108 and the limit switch 14, which was closed by opening the interior door 8. The relay winding 108 then closes motor contacts 110-110 and holding contacts 30 112 to reverse the motor 94 to close the interior door. As the interior door is moved closed, the limit switches 96 and 98 are closed successively, and the limit switch 14 is opened at the extreme of the closing movement, thereby deenergizing the motor 94.

35 If it is desired to open the interior door 8 only to its partially open position, one of switch contacts 120 and 122 is opened manually, thereby closing the corresponding one of the contacts 124 and 126 which closes the circuit to the relay winding 128. This closes holding contacts 130 and contacts 132, and opens the switch contacts 134 to prevent operation of the circuit for opening the interior door to its fully open position. Closing 40 of contacts 130 keeps the relay winding 128 energized and closing of the contact 132 causes energization of the relay winding 88 to run the motor 94 in a door-opening direction. As the interior door reaches its partially open position, the lug 50 94 opens the limit switch 98 to stop the door at that position. The door may be closed as described hereinabove in closing it from its fully open position.

55 Whenever the interior door 8 is closed, the limit switch 14 is opened by the lug 15 (Fig. 3) to deenergize the relay winding 16 so that the contacts 140 reclose to permit the exterior door to be opened. Whenever the interior door is opened even partially, the switch 14 is closed to prevent opening the exterior door. Similarly, whenever the exterior door 7 is closed the limit switch 42 is opened so that the relay winding 44 is deenergized, thereby closing contacts 142 to permit operation of the interior door, and if the exterior door is opened even partially, the switch 42 is closed to cause opening of the contacts 142, thereby preventing opening the interior door.

What is claimed is:

1. A door control system, which comprises a chamber having an entrance doorway and an exit doorway, an entrance door mounted in the entrance doorway for movement between an open position and a closed position, a second door mounted for movement in the exit doorway, a reversible electric motor for moving the entrance

door, a source of electrical power, a limit switch closable by the second-mentioned door when the second-mentioned door is not closed, a second reversible electric motor for moving the second-mentioned door, a second limit switch closable by the entrance door when the entrance door is not closed, a blocking relay having a winding in series with the first-mentioned limit switch and the source of electrical power and contacts for preventing operation of the first-mentioned motor when the second-mentioned door is not closed, a second blocking relay having a winding in series with the second-mentioned limit switch and the source of electrical power and contacts for preventing operation of the second-mentioned motor when the first-mentioned door is not closed, means including a manually operable switch having normally open contacts in parallel with the winding of the first-mentioned relay and the first-mentioned limit switch for actuating the second-mentioned motor to open and close the second-mentioned door, and means including a manually operable switch having normally open contacts in parallel with the winding of the second-mentioned relay and the second-mentioned limit switch for actuating the first-mentioned motor to open and close the first-mentioned door.

2. A door control system, which comprises a chamber having an entrance doorway and an exit doorway, an entrance door mounted in the entrance doorway for movement between an open position and a closed position, a second door mounted for movement in the exit doorway, a reversible electric motor for moving the entrance door, a source of electrical power, a limit switch closable by the second-mentioned door when the second-mentioned door is not closed, a second reversible electric motor for moving the second-mentioned door, a second limit switch closable by the entrance door when the entrance door is not closed, a blocking relay having a winding in series with the first-mentioned limit switch and the source of electrical power and contacts for preventing operation of the first-mentioned motor when the second-mentioned door is not closed, a second blocking relay having a winding in series with the second-mentioned limit switch and the source of electrical power and contacts for preventing operation of the second-mentioned motor when the first-mentioned door is not closed, a lock switch having contacts in series with the winding of the first-mentioned relay and the source of electrical power and contacts in series with the winding of the second-mentioned relay and the source of electrical power for selectively connecting and disconnecting the windings to and from the source of electrical power, means including a manually operable switch having normally open contacts in parallel with the winding of the first-mentioned relay and the first-mentioned limit switch for actuating the second-mentioned motor to open and close the second-mentioned door, and means including a manually operable switch having normally open contacts in parallel with the winding of the second-mentioned relay and the second-mentioned limit switch for actuating the first-mentioned motor to open and close the first-mentioned door.

3. A door control system, which comprises a room having a doorway, a door movable with respect to the doorway between closed position, a partially open position and a fully open position, a source of electric power, a reversible motor for moving the door, means including a relay

having a relay winding and contacts for connecting the motor to the source of power to energize the motor to open the door when that winding is energized, means including a second relay having a relay winding and contacts for connecting the motor to the source of power to energize the motor to close the door when that winding is energized, a limit switch closed when the door is in its closed position, openable by the door when the door arrives at its fully open position and connected in series with the winding of the first-mentioned relay and the source of power, a second limit switch closed when the door is not in its closed position, openable by the door when the door arrives at its closed position and connected in series with the winding of the second-mentioned relay and the source of power, a third limit switch closed when the door is in its closed position, openable by the door when the door arrives at its partially open position and connected in series with the winding of the first-mentioned relay and the source of power and in parallel with the first-mentioned limit switch, a manually operable, normally open, switch connected in series with the relay winding of the second-mentioned relay and the second-mentioned limit switch and in parallel with the third-mentioned limit switch, a second manually-operable, normally open, momentary switch connected in series with the relay winding of the first-mentioned relay and the first-mentioned limit switch, a third relay including a relay winding connected in series with the source of power and the third-mentioned limit switch and in parallel with the relay winding of the first-mentioned relay, normally open contacts in series with the winding of the first-mentioned relay and the third-mentioned limit switch and in parallel with the first-mentioned manually operable switch and normally closed contacts in parallel with the last-mentioned contacts and in series with the first-mentioned manually operable switch and the first-mentioned limit switch, and a third manually operable, normally open switch in series with the second-mentioned limit switch and the winding of the second-mentioned relay.

4. A door control system, which comprises a room having a doorway, a door movable with respect to the doorway between closed position, a partially open position and a fully open position, a three-phase electric power source, a reversible three-phase motor for moving the door, means including a relay having a relay winding and contacts for connecting the motor to the source of power to energize the motor to open the door when that winding is energized, means including a second relay having a relay winding and contacts for connecting the motor to the source of power to energize the motor to close the door when that winding is energized, a limit switch closed when the door is in its closed position, openable by the door when the door arrives at its fully open position and connected in series with the winding of the first-mentioned relay and the source of power, a second limit switch closed when the door is not in its closed position, openable by the door when the door arrives at its closed position and connected in series with the winding of the second-mentioned relay and source of power, a third limit switch closed when the door is in its closed position, openable by the door when the door arrives at its partially open position and connected in series with the winding of the first-mentioned relay and the

source of power and in parallel with the first-mentioned limit switch, a manually operable, normally open, momentary switch connected in series with the relay winding of the first-mentioned relay and the first-mentioned limit switch and in parallel with the third-mentioned switch, a second manually operable, normally open, momentary switch connected in series with the relay winding of the second-mentioned relay and the second-mentioned limit switch, a third relay including a relay winding connected in series with the source of power and the third-mentioned limit switch and in parallel with the relay winding of the first-mentioned relay, normally open contacts in series with the winding of the first-mentioned relay and the third-mentioned limit switch and in parallel with the first-mentioned manually operable switch and normally closed contacts in parallel with the last-mentioned contacts and in series with the first-men-

5

tioned manually operable switch and the first-mentioned limit switch, and a third manually operable, normally open, momentary switch in series with the third-mentioned limit switch and the winding of the third-mentioned relay, each of said relays including holding contacts in parallel with the manually operable switches in series with the relay windings thereof.
